SELF-CONTAINED DISPENSING CAN

Laurence J. Stovel, Richmond, Calif.

Application July 31, 1939, Serial No. 287,462

3 Claims. (Cl. 146—61)

The invention, in general, relates to means for removing material from a container. More particularly, the invention relates to a non-refillable can containing in itself means for dispensing desired quantities of the contents thereof.

While the invention has been directed primarily to the dispensing of material having the consistency of paste, such as various types of soap including the so-called mechanics' soap, embodiments of the invention can embrace means for dispensing granulated and powdered material effectively, as well. Accordingly, the illustrations and following description will be directed to both of the foregoing aspects of the invention.

A primary object of the invention is to provide a non-refillable, self-contained dispensing can affording ready removal of desired quantities of the contents thereof without waste and without deleteriously affecting the contents remaining in the can at any time.

Another object of the present improvement is to provide a dispenser of the indicated nature which is dependable in operation and which can be used effectively without likelihood of injury to the user.

A still further object of the invention is to provide a self-contained dispensing can which is characterized by substantial sealing of the contents thereof at all times, and by its simplicity of dispensing elements.

Another object of the present invention is to provide a dispensing can of the aforementioned character which is relatively inexpensive to manufacture.

A still further object of the invention is to provide a self-contained dispensing can which can be used effectively either when suspended from a support or without suspension thereof in any way whatsoever.

The foregoing and other objects are attained in the preferred and modified embodiments of my invention illustrated in the accompanying drawing. It is to be understood that I am not to be limited to the precise embodiments shown, nor to the precise arrangement of parts, as the invention, as defined in the appended claims, can be embodied in a plurality and variety of forms.

Referring to the drawing:

Figure 1 is a vertical sectional view of a preferred embodiment of the present invention.

Figure 2 is a sectional view taken on the line 2—2 of Figure 1.

Figure 3 is a perspective view of the preferred embodiment of my self-contained dispensing can.

Figure 4 is a perspective view of a modified embodiment of the present improvement.

Figure 5 is an enlarged detail of a portion of the modification shown in Figure 4.

Figure 6 is an enlarged plan view of a closure for the modified embodiment of the invention shown in Figure 4.

In its preferred form, the self-contained dispensing can of my invention preferably comprises a cylindrical body, a flanged disc closing one end of said body and permanently fastened thereto, a second flanged disc movably attached to the other end of said body, a charge of material within said body and supported on said second disc, together with means on said second disc for severing a portion of said charge when said second disc is moved relative to said body, and means within said body for constraining movement of said charge when said second disc is moved.

I am familiar with nearly all of the dispensing containers in present use and none of these is what may be aptly or accurately termed a self-contained dispenser since they all require extrinsic means for effecting the removal of the contents and also for advancing the charge to a severing element. The present invention contemplates no extrinsic element in that connection, but, rather, utilizes the weight of the contents to maintain the charge in position at all times for the severing action and the removal of desired quantities of the contents at will.

In accordance with the present improvements, I provide a cylindrical hollow body 11 which preferably is fabricated of a metal such as tin or aluminum but which can be made from a wood pulp or of cardboard, or from a phenolic condensate, as desired. In Figure 1 of the drawing, I have illustrated an embodiment of the invention especially suitable for dispensing material having a paste consistency, such as a mechanics' soap, and the body 11 is filled with a charge 12 thereof. Preferably, one end of the body 11 is tightly sealed with a disc closure 13 provided with a peripheral flange 14 that is crimped around and interlocked with a flange 16 on the longitudinal extremity of the body 11. Since the packing of the can with material of paste consistency is usually under a vacuum, the closure 13 may be punched out to release the vacuum but otherwise the closure 13 forms a perfect seal at that end of the body. At the other end of the body 11 I provide a second disc closure 17 which preferably is formed with a flange 18 having a bead 19 thereon, the bead defining an interior track 20 into which is fitted

a turned-over flange 21 formed on the other longitudinal extremity of body 11. The closure 17, by this connection, is adapted to be rotated relative to the body yet, nevertheless, is effectively fastened to the body against removal therefrom except with the use of a tool. Preferably, the bead 19 is knurled to facilitate turning the disc closure 17 when it is desired to remove desired quantities of the charge 12.

As illustrated particularly in Figures 2 and 3 of the drawing, the closure 17 is formed with an arcuately shaped slot 22 therein which extends from the exact center of the disc closure to the periphery thereof and which is tapered, as shown. The slot 22 conveniently is formed by first cutting through the material of the closure to the aforesaid shape and then bending the material inwardly as well as slightly deforming the same to provide an arcuately shaped, inwardly extending severing element 23 which likewise is tapered as a result of so forming the slot 22. Thus, there is afforded a severing element which has a relatively high portion adjacent to the center of the disc closure 17 and a relatively low portion adjacent to the periphery of the disc. This shape of severing element 23 is highly advantageous for a more effective slicing of the charge 12. For, at the center of the bottom of the charge 12, the severing element 23 will bite into the charge for an appreciable distance and, as the closure 17 is rotated, will slice from the entire area of the bottom of the charge from the center to the circumference thereof rather than bore a hole into the charge at the center and leave a ridge or wall adjacent to the circumference of the bottom of the charge. It is to be particularly observed that the body 11, in use, is disposed with the disc closure 13 at the top thereof and with the disc closure 17 at the bottom and that, in this position, the charge 12 is almost entirely supported by the closure 17 and is always in engagement with the severing element 23 regardless of the diminution of the charge by dispensing portions thereof from time to time. In other words, the severing element 23 is always embedded in the charge 12.

In addition to the foregoing elements, the self-contained dispensing can of my invention includes a baffle plate or fin 24 which is fastened interiorly of the body 11 between the end closures 13 and 17 and which extends substantially the entire length of the body terminating adjacent to the severing element 23. Preferably, the fin or baffle plate 24 is formed to a width so that it appreciably penetrates into the charge 12, as shown. The fin 24 effectively prevents movement of the charge in a direction other than longitudinally of the body or can. Hence, when the closure disc 17 is turned to effect movement of the severing element 23 through the charge to sever portions thereof and guide the severed portions out of the can through the slot 22, the rotation of the disc 17 is not imparted to the charge 12 by reason of the restraining action of the baffle plate 24, and since the baffle plate extends nearly the length of the can its restraining action is effective for the life of the dispenser as the charge is diminished gradually by the severing of portions of the same when desired. It is clear that an effective manner of manipulating the disc 17 to dispense the charge is to place the fingers around the knurled bead 19 with the palm of the hand up to receive the severed portion of the charge as it drops through the slot 22.

It is to be understood, of course, that the engagement between the closure disc 17 and the

cylindrical body 11 is such as to provide an interlock longitudinally so that the lid or closure disc 17 cannot be removed from the body 11 unless a tool is used to force the same therefrom. In that event, it is clear that the flange of the disc 17 or the flange 21 of the body 11 is so distorted that the effectiveness of the dispenser is greatly impaired or entirely destroyed. In that sense, the dispensing can of my present improvement is non-refillable for once the joint between the closure 17 and the body 11 is impaired or destroyed the closure will not effectively rotate relative to the body and its dispensing property is lost.

As indicated above, the self-contained dispensing can of the present improvement may be effectively used without suspending the same from a support of any character since it is only necessary to lift the can with one hand and rotate the closure 17 with the other. However, the dispenser can be suspended from any suitable support and I have illustrated a convenient form of suspension in Figure 1 of the drawing. Preferably, I provide a supporting bracket 27 including a leg 28 provided with suitable holes 29 for passing screws 31 to attach the bracket to a wall 32 or other support. The bracket 27 includes a leg 33 preferably disposed at right angles to leg 28 and on which is carried a down-turned clip 34 for engaging the flange 14 of the closure 13 of the can. Leg 33 of the bracket is also provided with a downwardly extending spring-clip 36, preferably formed on the bracket by striking out a portion of the material of which the leg 33 is fabricated, as shown; the clip 36 being formed with a shoulder 37 which underlies the external flange 14 of the closure 13 of the can. A resilient spring or yieldable clip 35 extends from leg 28 of the bracket to engage the body 11 of the can. To mount the dispensing can on the bracket, it is only necessary to fit the flange of the closure 13 into the clips 34, 36 and snap it into suspended position, the clips gripping the can at diametrically opposite points of the flange formed on the closure 13. If desired, another leg 38 can be provided on the bracket 27 below and parallel to leg 33, and the outer end of leg 38 can be arcuately shaped to fit the body portion 11 of the can and brace the same.

Since material packed in cans often is under a vacuum, it is generally desirable to puncture the can to release the vacuum and thus facilitate removal of the contents. This is especially true in the case of material in paste form, such as mechanics' soap. In the embodiment of the invention designed for dispensing soap of that character, I find it desirable to puncture the closure member 13. To effect this result when suspending the can from a fixed support, such as on the bracket 27, a spike 39 can be located on leg 33 of the bracket in the path of the closure 13 as the can is being mounted. Thus, the closure 13 will be punctured in fitting the can to the bracket. It is clear that in suspending the can from a support, such as the bracket 27, the charge 12 is supported in the main by closure 17 of the dispenser, and the rotation of the dispenser relative to the body 11 effects a dispensing of the charge through slot 22 of the closure 17.

In the views numbered Figures 4 to 6 inclusive, I have shown a modified embodiment of my present improvement which is especially suitable for dispensing granulated or powdered material. The cylindrical body portion 11 of this modification is effectively sealed by a closure

which is permanently and immovably fastened thereto. At the opposite end of the body 111, I fasten a cover 117 so as to be relatively rotatable with respect to the body portion 111 but which cannot be moved longitudinally therefrom without the use of some tool. Lid or closure 117 is provided with a plurality of openings 122 by striking out portions of the lid to form a plurality of relatively small guides 123. Preferably, each guide 123, is formed with parallel sides and an arcuate end, as shown, the guides extending interiorly of the body a relatively short distance. No cutting edges are provided on the guides 123. It is to be understood that in the manufacture of the closure 117, the same may be scored rather than cut, in the manner above described, so that subsequently a user may punch out the guides 123 and form the openings 122. Upon relative rotational movement between closure 117 and the body 111 of the dispensing can, the powdered or granulated material will pass through or be discharged from the openings 122. While no support is needed to suspend the dispensing can 111, the same can be suspended from a bracket similar to the bracket depicted in Figure 1 of the drawing. It is, of course, to be understood that the material will not sift through openings 122 unless the closure 117 is being rotated. Moreover, the openings 122 and guides 123 may extend over substantially the entire area of the closure 117 or may be confined to one quadrant thereof, as shown in Figures 4 and 6.

It is to be understood that the appended claims are to be accorded a range of equivalents commensurate with the advance made over the prior art.

I claim:

1. A self-contained dispensing can especially suitable for the dispensing of soap and the like, said dispensing can consisting of a hollow cylindrical body adapted to receive and hold a charge of soap, a closure immovably fastened to and sealing one end of said body, a disc closure rotatably mounted on the other end of said body and adapted to be gripped and turned by the hand; said disc closure having an arcuately shaped, tapered slot therein extending from the exact-

center of the disc closure to its periphery with the wider portion of the slot adjacent to the center of said disc closure, and an arcuately shaped, tapered severing element on said disc closure projecting within said body; said tapered severing element having its wider portion adjacent to the center of said disc closure, said severing element including a cutting edge and a wall which constitutes the side wall of said slot over which cut material from a charge in said body is guided to and through the slot.

2. A self-contained dispensing can consisting of a hollow, cylindrical body adapted to receive and hold a charge of soap or the like, a closure immovably fastened to and sealing one end of said body, a disc closure rotatably mounted on the other end of said body and adapted to be turned by the hand; said disc closure having an arcuately shaped, tapered slot therein extending from its center to its periphery with the wider portion thereof at the center of said disc closure, a fin fastened interiorly of said hollow body to project radially toward the center of the body and extending substantially the entire length thereof, and an arcuate, tapered severing element on said disc closure projecting into said hollow body and having its wider portion adjacent to the center of said disc closure; said severing element including a cutting edge and a wall which constitutes the side wall of said slot over which cut material from a charge in said body is guided to and through the slot upon rotation of said disc closure, said fin constraining the charge against movement during the severing action.

3. In a dispensing can, a disc closure rotatably mounted on one end thereof for turning by the hand; said disc closure having an arcuate tapered slot therein extending from its center to its periphery, said slot being wider adjacent the center of said closure, and an arcuate, tapered cutting element on said disc closure projecting into the can and having its wider portion adjacent to the center of said disc closure; said severing element including a cutting edge and a wall which constitutes the side wall of said slot.

LAURENCE J. STOVEL.
